MOUNTING FOR VEHICLE DOORS AND THE
LIKEBion C. Place, Detroit, Mich., assignor of one-half
to George E. Gagnier, Detroit, Mich.

Application November 15, 1930, Serial No. 495,995

7 Claims. (Cl. 296—44)

This invention relates to mountings for pivoted closure elements such, for example, as vehicle doors and the like. It is the general object of the present invention to provide an improved mounting arrangement of this type and, more specifically, to design such a mounting for particular application to the doors of automobile bodies.

The common practice in present day vehicle body construction is to mount each of the doors upon a pair or more of individual spaced hinges of a conventional type. The door, especially one of all metal construction, and having a plate glass window, is too heavy to be properly supported in this fashion. It will sag when open and the individual hinges will become distorted or loosened through constant use. Sagging and distortion cause the door to swing improperly, with consequent difficulty in closing it and with difficulty in bringing the several latch portions into interengaging alignment. Manufacturers have attempted to re-enforce the individual hinges, and have placed coacting lugs and sockets on the body and the unhinged side of the door respectively to provide additional support for the door when closed. The door and body are thus locked together at a plurality of points and hence, when the body becomes momentarily slightly twisted or subjected to shock, as the vehicle passes over road irregularities, rattling and squeaky noises emanate from the numerous points of interlocking.

A further undesirable feature of the old type hinges is that they project outwardly beyond the vehicle body to destroy its otherwise pleasing streamline effect, and to place oil and accumulated dirt where it can be wiped off easily and inadvertently by the clothing of those persons using the automobile.

As recommended by the distributors in the automotive industry, the doors must be kept closed at all times when not in use in order to prevent sagging and to prevent them from being inadvertently damaged or torn off by trees or the like when the vehicle is put into motion. This recommendation must be observed because the doors are manually, and not automatically, closed. Due to the lack of automatic closure, and the provision of a relatively expensive latch mechanism that must work with precision and accuracy in order to help support the door and maintain it tightly closed, it is often necessary to slam the door with great force in order to cause the bolt to enter into its keeper. This results in breakage of glass, and wear and distortion of the hinges. Moreover, since no means, auxiliary to the latch, is provided for maintaining the door in closed position, the latter is

likely to swing open when an occupant is leaning thereagainst, with dire results if the vehicle is in motion.

Accordingly, the major objects of the present invention are to improve upon present-day hinges and door mountings and to remedy the defects and disadvantages pointed out in the preceding discussion. The general and more specific objects, through which my major objects are accomplished, are as follows:

It is an object of my invention to design an improved mounting or hinge, for swinging doors, which will in itself provide a sufficient support for the door throughout the life of the latter and regardless of what position the latter may be in. This may be accomplished without reenforcement and without the provision of additional supporting devices at the latched side of the door.

Another important object of the present invention is that of providing a hinge structure for an automobile door or the like, which structure shall be invisible from the outer side of the door in all positions of the latter.

A further object of this invention is to provide an automobile door mounting which will serve to close the door automatically and to resist opening movement of the latter; which will substantially eliminate the usual rattles and squeaks caused by relative movement between the door and the body; and which will permit the use of an inexpensive latch with relatively loosely interfitting parts.

Still another object resides in the provision of a spring-closed automobile door in combination with a checking device for preventing too rapid closing movement that might break the glass, distort the hinges or cause personal injuries. In this connection it is an important object to dispose the checking device in a concealed position.

These and further objects will more fully appear from a study of the following detailed description of preferred embodiments of the invention illustrated in the accompanying drawings.

In the drawings:

Figure 1 is a view, in outside elevation, of a door mounted at its pivotal edge upon a portion of an automobile body in the manner contemplated in the present invention.

Figure 2 represents a side elevational view of the right side of the structure of Figure 1.

Figure 3 shows, in enlarged perspective when looking at the door from its inner side, an upper corner of the door together with a portion of the preferred hinge structure and a checking device. The supporting pillar of Figures 1 and 2 has been

removed, as have also the interior trimming panels, fabrics and the like.

Figure 4 constitutes a view in elevation of the inner side of a supporting pillar,—that is, the side which receives the hinge structure of Figure 3.

Figure 5 is an enlarged section taken substantially along the plane of line 5—5 in Figure 3, but with the pillar of Figure 4 combined with the hinge structure in proper relationship for closed door position. Open position of the door is shown in broken lines.

Figure 6 is a section similar to that of Figure 5, but taken along the plane of line 6—6 in Figure 3.

Figure 7 is a detailed view of one of the springs employed in the hinge structure of Figures 3, 5 and 6.

Figure 8 is an enlarged partial section taken along the vertical plane of line 8—8 in Figure 3, and with a portion of the vehicle body and interior trimming added to show the manner in which the checking device is concealed and associated with the body.

With further reference to the drawings, wherein like numerals are employed to designate like parts, numeral 10 indicates a door forming a part of the body of a vehicle (not shown). The door is supported by a pillar 12 for swinging movement about a vertical axis. The pillar may be a conventional upright post of the vehicle frame revamped to adapt it for receiving and concealing the hinge structure (later described), or it may be a specially designed casing in the form of a post adapted to be built into the body structure.

Because of its peculiar shape and functions hereinafter appearing more fully, the pillar may properly be called either a part of the vehicle body or a part of the hinge structure.

With particular reference to Figures 3, 5 and 6, the pivoted edge of the door has secured thereto, as by rivets or spot welding, a strengthening and supporting strip of metal 14. The strip 14 is L-shaped in horizontal section and extends vertically substantially throughout the length of the door. Along its vertex or line of bending, the strip 14 has a plurality of spaced slits 15 cut therein in vertically aligned relationship to receive portions of a specially designed multiple-fingered hinge leaf, designated generally by numeral 16.

The leaf 16 comprises an elongated, flat vertical strip 17 rigidly secured to the edge of the door by the same rivets, 13, which fastened the element 14 to the door, and further comprises a plurality of spaced fingers 18 formed integral with the strip 17. As illustrated, these fingers preferably are formed by bending, in each instance, a single horizontal and narrow strip of material of the main strip 17 to form a curved loop terminating in a cylindrical sleeve 19 (see Figure 5). After the formation of the sleeve, the strip is bent backwardly upon itself until its free end 20 reaches the main strip 17, and thence it is passed through one of the slits 15 of the angle member 14. The end 20 is then riveted, as at 21, into engagement with the interior side of the longitudinal face of the angle member.

The hinge leaf under discussion thus comprises a plurality of vertically spaced and aligned sleeves 19 that are maintained in a fixed position relative to the door. This relative fixed position may become of prime importance, as will be explained later, but it should be understood that multiple

fingers may be formed by other methods and in other ways than that just outlined. The number of fingers necessary is determined by the weight of the door, and by the length of the latter. They may continue throughout the length of that portion of the door which is flat and of uniform thickness. (Some vehicle doors are gradually curved to form a thin lower edge, as seen in Figure 2.) The sleeves 19 receive a common cylindrical pin 22 which passes vertically therethrough to provide a pivotal axis for swinging movement of the door. The other leaf of the hinge, that is, the one which supports the pin 22 to fix its axis with respect to the body of the vehicle, will now be described.

A sheet metal angle bar 23, L-shaped in horizontal cross section and elongated vertically to substantially the same length as the angle bar 14, is utilized to mount the pin 22 on the vehicle body. One wing, 24, of the bar 23 is in surface contact with the metal strip 17, when the door is in its illustrated closed position, and is slotted opposite each looped finger 18 to provide a plurality of spaced supporting tabs 25 which alternate with the fingers 18 throughout the length of the hinge. Each tab 25, except the top one, is freely disposed between a pair of the fingers 18, and each tab has a hole 26 for the reception of a screw 27 that fastens it to the pillar 12 in a manner later to be described.

The other wing, 28, of the angle bar 23 is shaped to provide a plurality of spaced fingers 29 each of which, except the top one, is spaced between a pair of the fingers 18 and is of a width about one half as great as the distance between the fingers 18. The free ends of the fingers 29 are rolled or bent to form a set of cylindrical sleeves 30 in alignment with the sleeves 19 of the other hinge leaf. The long pin 22 passes vertically through the sleeves 30 as well as the sleeves 19, and is provided with a head 31 for limiting its downward movement.

The pillar 12 (see Figures 4, 5 and 6), comprises an elongated U-shaped channel member 32 of substantially the same thickness as the door, the ends of this member being firmly supported by the body structure (not shown). The open side of the channel faces the door hinge and receives the latter to completely conceal it from external view. At spaced intervals one side of the channel member carries a set of integral lugs 33, each of which is parallel to and directly opposite one of the tabs 25 of the stationary hinge leaf. The lugs 33 are provided with threaded openings 34 for the reception of the threaded ends of the screws 27 that pass through the tabs 25, whereby the tabs 25 are firmly locked stationarily upon the lugs 33. The holes 34 may be elongated vertically if desired, and floating nuts placed behind them to receive the threads of screws 27, in this manner providing for a vertical adjustment of the entire door. The looped fingers 18 of the swinging hinge leaf are freely received in the channel member between the lugs 33, and hence are permitted to oscillate in the channel without restriction as the door is opened or closed.

In order to increase the rigidity of the channel member 32 and to strengthen the supporting lugs 33, an elongated bridging element 35 of special shape is built into the channel of the pillar. This element comprises a strip of sheet metal 36 extending throughout the length of the pillar and crimped, as at 37, into engagement with the inner surface of one side of the channel member. It has a plurality of offset integral

5 fingers bent through several right angles to form a corresponding plurality of bridges, each of which is directly opposite a lug 33 and comprises three wings, 38, 39 and 40. The wings 40 are of the approximate shape of the lugs 33, and are interposed between said lugs and the tabs 25. The threaded holes 34 of the lugs continue through the wings 40, and hence the lugs, the wings and the tabs are rigidly clamped together 10 by the screws 27. The bridging element 35 has been given its special design in order that it may not interfere with the free oscillation of the hinge elements 18.

From the description thus far given, it will be seen that the door is free to swing outwardly from the vehicle body (in a counterclockwise direction in Figures 3, 5 and 6) about the axis of the pin 22 as illustrated in broken lines in Fig. 5. Since the hinge structure is disposed entirely behind the 20 plane of the outer door surface and is receivable by the pillar 12, it is completely concealed from the view of one standing beside the vehicle, and this is true whether the door is open or closed. Nothing projects beyond the streamline surface 25 of the body. The location of the axis of oscillation is important in a concealed hinge arrangement of this nature, since its disposition must be such that none of the swinging parts will bindingly engage any of the stationary parts when the door 30 is swung. The outer edge of the door is flanged, as at 41, adjacent the crimped edge 37 of the pillar. These flanged and crimped edges may easily be brought into overlapping relationship when the door is closed, simply by prolonging the edge 37 35 and bending it to fit under the edge 41, and redesigning the hinge to proportion the parts so that they will permit the door to swing in spite of the overlapped relationship. The door being pivotally supported continuously throughout a 40 substantial portion of its left, the door weight is uniformly distributed along the pillar, the door will not sag or cause hinge distortion, and no auxiliary supports at the free side of the door are necessary.

45 I prefer to add further means to the hinge structure for the purpose of obtaining automatic door closure and for resisting the opening movement of the door. With reference to Figures 3, 5, 6 and 7, this means is as follows:

50 A plurality of resilient devices 42, one individual to each hinge leaf finger 18, are associated with the oscillating and stationary hinge leaves to react therebetween. Each device 42, (Figure 7) comprises a single continuous spring wire bent to 55 provide a pair of spaced coils 43 interconnected by a straight reactance loop 44. The terminals of the spring device project from the outer sides of the coils 43 to form a pair of parallel reactance arms 45.

60 The spring devices are so arranged in combination with the hinge that each is under tension with its coils pierced by the pin 22, its loop 44 reacting against a finger 18 of the oscillating hinge leaf and its arm 45 reacting against the strip 23 of the stationary hinge leaf. The effect 65 of these reactances is to urge the door toward its closed position and to yieldingly resist opening movement thereof. As the door is pushed open the fingers 18 oscillate and pull the spring loops 44 with them in a manner to wind up (tighten) the coils of the spring device and hence to increase the tension of the latter.

70 Where the combination just described is utilized, it is impossible to leave a door open inadvertently with the risk of its being torn off or

damaged. The usual rattling and squeaking when a car is in motion is eliminated, since the edges of the door are always uniformly and yieldingly urged toward the adjacent surfaces surrounding the opening in the vehicle body. This action 80 further eliminates the need for an expensive latch mounted so accurately that the door must be slammed with great force to permit the bolt to enter its keeper. All that is necessary, where the present invention is adopted, is the provision of any simple, inexpensive latch with loosely fitting parts, for positively preventing the door from opening on the road and for locking it when parked. The door will thus close and latch itself without manual slamming, and hence there is no danger of glass breakage or hinge distortion.

85 I prefer to use that portion of the invention, already described, in combination with a checking device for preventing too rapid closing movement of the door. No harm is ordinarily done where the spring devices of the hinge are relatively light so that their strength is sufficient to close the door without forceful and rapid movement. However, if the springs are made strong enough to increase their tension and quicken their action, 90 it becomes desirable to provide a check to prevent glass breakage and possible personal injuries when the door swings shut.

95 With reference to Figures 3 and 8 there is illustrated a preferred form of checking arrangement wherein the check device is completely concealed. The arrangement comprises a closed cylinder 46 normally lying longitudinally of the upper edge of the door within a recess 47 cut or formed in the latter. That end of the cylinder 100 adjacent the hinge has an integral lug 48 which receives a vertical bolt 49 and is designed to pivot about the latter. The threaded end of the bolt projects upwardly through a portion 50 of the vehicle body (see Figure 8) and is locked in fixed 105 position relative to the body by a nut 51.

110 A plunger 52 fits for reciprocation within the cylinder and is secured to a rod 53 which projects outward through the free end of the cylinder. The projecting end of the rod is bent and shaped to form an eye 54 which pivots about a screw-bolt 55. The latter passes through the eye and that horizontal surface of the door which forms the bottom of the recess 47. A nut 56 locks the bolt 55 in vertical position on the door. An 115 interior trim panel 57 or the like (shown only in Figure 8) extends past the vehicle body to cover the open side of the recess 47 and hence to completely conceal the checking device when the door is closed.

120 As the door is swung upon its hinge it will be seen that the checking device may oscillate horizontally about the bolts 49 and 55, the plunger simultaneously reciprocating to a certain extent within its cylinder. Reciprocation of the piston in either or both directions may be resisted to check the door in any conventional manner. The piston may have a restricted longitudinal passage therethrough and the cylinder filled with a fluid, thus providing a dash-pot action (as 125 shown). Other types of fluid brakes might be employed, or a coil spring interposed between the plunger and an end of the cylinder. The checking device per se, however, forms no part of this invention and hence is but diagrammatically illustrated. It is added merely to show the method of its concealment and the general combination in which it functions as a part.

130 The invention may be embodied in other specific forms without departing from the spirit or

essential characteristics thereof. The present embodiment is therefore to be considered in all respects as illustrative and not restrictive, the scope of the invention being indicated by the 5 appended claims rather than by the foregoing description, and all changes which come within the meaning and range of equivalency of the claims are therefore intended to be embraced therein.

What I claim and desire to secure by United 10 States Letters Patent is:—

1. In combination with a door and a supporting structure including a vertical mounting pillar upon which the door is designed to be swingingly mounted, a hinge structure disposed entirely 15 between the planes of the door's side surfaces, said hinge structure comprising a pair of complementary hinge leaves secured to said door and said supporting structure respectively, and each provided with a plurality of pivotally aligned 20 integral fingers concealed from external view within said pillar, the fingers of one leaf alternating with those of the other continuously throughout a substantial portion of the length of the hinged side of said door, and a single elongated pivot pin for interconnecting the sets of 25 fingers.

2. In combination with a door and a supporting structure upon which the door is designed to be swingingly mounted, a hinge structure disposed entirely 30 between the planes of the door's side surfaces, said hinge structure comprising a pair of complementary hinge leaves secured to said door and said supporting structure respectively, and provided with a plurality of pivotally aligned 35 fingers, the fingers of one leaf alternating with those of the other continuously throughout a substantial portion of the length of the hinged side of the door, a single elongated pivot pin for interconnecting the sets of fingers, and spring means reacting 40 between one leaf and the complementary fingers of the other leaf to urge said door toward closed position at all times, said hinge structure, including the spring means, being concealed between said door and said supporting structure.

3. A mounting for closure elements such as vehicle doors and the like, said mounting including a pair of hinge leaves, one of said leaves being designed to have its body portion rigidly supported and to form a plurality of spaced fingers terminating in substantially cylindrical sleeves, the 50 other one of said leaves being designed to have its body portion attached to a closure element and to form a plurality of spaced fingers terminating in substantially cylindrical sleeves in alternating alignment with the first mentioned sleeves and spaced slightly therefrom, a pin inserted through all of the alternating sleeves, and spring means reacting between said leaves to cause one of them to tend to swing about the axis of said pin relative to the other, said spring means comprising 55

coil springs surrounding said pin between the spaced cylindrical sleeves of said fingers and having extensions in torsional engagement with portions of said leaves.

4. A mounting for closure elements such as vehicle doors and the like, said mounting including a pair of hinge leaves, one of said leaves being designed to have its body portion rigidly supported and to form a plurality of spaced fingers terminating in substantially cylindrical sleeves, the other one of said leaves being designed to have its body portion attached to a closure element and to form a plurality of spaced fingers terminating in substantially cylindrical sleeves in alternating alignment with the first mentioned sleeves, and means pivotally interconnecting all of the alternating sleeves, the body portion of one of said leaves having spaced openings adjacent the fingers of the other leaves to permit free pivotal movement of the last mentioned fingers.

5. A mounting for closure elements such as vehicle doors and the like, said mounting including a pair of hinge leaves, one of said leaves being designed to have its body portion rigidly supported and to form a plurality of spaced fingers terminating in substantially cylindrical sleeves, the other one of said leaves being designed to have its body portion attached to a closure element and to form a plurality of spaced fingers terminating in substantially cylindrical sleeves in alternating alignment with the first mentioned sleeves, a pin inserted through all of the alternating sleeves, the body portions of the leaves being in parallel engagement when in one of their extreme positions, and a plurality of springs reacting 110 against the fingers of one leaf and the body portion of the other leaf with a normal tendency to urge said body portions into said position of parallel engagement.

6. In combination with an automobile body or 115 the like and a door therefor, a mounting structure forming a rigid part of said body and designed to support said door, said door having a plurality of spaced hinge elements projecting from one of its edges, said mounting structure having a plurality 120 of openings for receiving said hinge elements and being designed to form a vertical channel, and there being an elongated pin disposed in said vertical channel to swingingly support said spaced hinge elements.

7. In the combination defined in claim 6, said mounting structure being designed to form a plurality of spaced supporting members adjacent said channel in alternating relationship with said spaced openings, and there being a plurality of 130 rigid extensions projecting from said supporting members into said channel to receive said elongated pin.

BION C. PLACE.
